UNITED STATES PATENT OFFICE

140,627

DESIGN FOR A PIPE WRENCH OR THE LIKE

Alfred A. Armenta, Los Angeles, Calif., assignor
to Electrical Development Company, Los Angeles, Calif., a partnership

Application October 30, 1944, Serial No. 116,064

Term of patent 14 years

(Cl. D54—16)

To all whom it may concern:

Be it known that I, Alfred A. Armenta, a citizen of the United States and a resident of the city of Los Angeles, in the county of Los Angeles and State of California, have invented a new, original, and ornamental Design for Pipe Wrench or the like, of which the following is a specification, reference being had to the accompanying drawing, forming part thereof.

In the drawing:

Fig. 1 is a side elevational view of a pipe wrench showing my new design;

Fig. 2 is a top plan view;

Fig. 3 is a front end view; and

Fig. 4 is a handle end view thereof.

I claim:

The ornamental design for a pipe wrench or the like, substantially as shown.

ALFRED A. ARMENTA.
